BY *O. Davis*
ATTORNEY

UNITED STATES PATENT OFFICE.

ROBERT C. ALLEN, OF ESSINGTON, PENNSYLVANIA, ASSIGNOR TO WESTINGHOUSE ELECTRIC & MANUFACTURING COMPANY, A CORPORATION OF PENNSYLVANIA.

TURBINE BLADING.

Application filed April 18, 1922. Serial No. 554,704.

To all whom it may concern:

Be it known that I, ROBERT C. ALLEN, a citizen of the United States, and a resident of Essington, in the county of Delaware and State of Pennsylvania, have invented a new and useful Improvement in Turbine Blading, of which the following is a specification.

My invention relates to turbine blading, more particularly to exhaust blading of the wide type adapted to receive motive fluid, such as steam, at one side and to discharge it peripherally, and it has for its object to provide apparatus of the character designated which shall have relatively simple, easily installed, cheap, and efficient deflector members for changing the direction of the flow of steam between the blades.

Apparatus embodying features of my invention is illustrated in the accompanying drawings, forming a part of this application in which: Fig. 1 is a longitudinal sectional view of a turbine showing my improved blading applied thereto; Fig. 2 is an enlarged detail view of the upper right-hand portion of the wide blading in Fig. 1; and Fig. 3 is a diagrammatic view to illustrate the underlying principle of my invention.

In the application of Alexander T. Kasley, Serial No. 521,872 filed December 12, 1921, and assigned to the Westinghouse Electric and Manufacturing Company, there is disclosed and claimed a type of blade structure which is adapted to receive steam axially and to discharge it peripherally, the blades being provided with guide ribs which extend from the inlet sides to the outer, energy-abstracting portions. I provide guide means for the blades which are much shorter and which may be more readily manufactured and assembled than those disclosed in said application and which are capable of effectively changing the direction of the steam from an axial toward a radial direction.

Referring now to the drawings for a more detailed description of my invention, I show a turbine rotor 10, having journals 11, fitted in the bearings 12 of a casing or cylinder 13, the casing and rotor being provided with any suitable stages, for example, a multi-velocity impulse stage 14, followed by a plurality of fractional expansion stages 15, com-

posed of the stationary and moving blades 16 and 17 carried by the cylinder 13 and the rotor 10, respectively, and the latter are in turn followed by a last stage 18 composed of stationary guide blades 19 carried by the casing or cylinder and wide blades 20 adapted to receive steam axially and to discharge it peripherally.

The wide blades 20 are provided with inner approximately radial or plane portions 21 and outer curved or spoon-outline portions 22, the latter portions being adapted to expand and discharge steam peripherally at small angles. Each of the blades 20 is made up of a plurality of sections 23 for the purpose of facilitating manufacture, as disclosed and claimed in the application of Christian Gilson, Serial No. 554,988, filed April 18, 1922, and assigned to the Westinghouse Electric and Manufacturing Company.

I show a single set of guide members 24 for each blade section, the guide members extending from approximately an axial direction at the front of a section to a radial direction at the rear edge thereof; and the guide members are arranged successively lower, as shown in Fig. 1, from the inlet edge of the first blade section to the rear edge of the last section, thereby providing means for dividing the annulus of steam discharged between the blades into a plurality of annular portions for action upon the energy-abstracting portions 22, the guide members 24 being suitably curved so as to change the direction of flow from approximately an axial to a radial direction.

The guide members 24 may be secured to the blade sections in any suitable manner, for example, in Fig. 2, I show the guide members as being composed of contacting angle sections which are secured to their blade sections by means of rivets 25.

The principle of operation of my improved form of deflector guide members will be readily understood from a consideration of diagrammatic Fig. 3. In this view, there is shown an elbow conduit 27, in which fluid flows in the direction of the arrows. In a situation of this kind, it has been demonstrated that the best type of deflector to secure substantially a 90° change in the direction of flow of the fluid is a deflector which is curved transversely, somewhat like

an impulse turbine blade, so as to receive fluid tangentially at one edge, to gradually change its direction of flow, and to discharge it tangentially at the other edge. 5 This type of construction results in a change in the direction of flow along stream lines with a minimum loss due to eddying. I have, therefore, provided the sections of the relatively wide blades of the character referred to with successively lower curved deflector members which serve to change the direction of the annulus of steam from an axial toward a radial direction.

From the foregoing, it will be seen that 15 I have provided a relatively cheap, easily assembled, and efficient deflector structure for exhaust blading adapted to receive steam at one side and to discharge it peripherally.

20 While I have shown my invention in but one form, it will be obvious to those skilled in the art that it is not so limited, but is susceptible of various other changes and modifications, without departing from the 25 spirit thereof, and I desire, therefore, that only such limitations shall be placed thereupon as are imposed by the prior art or as are specifically set forth in the appended claims.

30 What I claim is:

1. In a turbine, a row of blades adapted to receive motive fluid at one side and to discharge it peripherally and a plurality of curved deflector members arranged successively lower from the outer portion of the inner side toward the inner portion of the outer side of each blade in order to change the direction of flow of the motive fluid passing between the blades from an axial toward a radial direction. 40

2. In a turbine, a row of blades adapted to receive motive fluid axially and to discharge it peripherally and curved deflector members carried by the blades for successively deflecting portions of the motive 45

fluid from an axial toward a radial direction.

3. In a turbine, a row of blades adapted to receive motive fluid axially and to discharge it peripherally, each blade being composed of a plurality of sections and curved deflector members secured to each of the sections and at different heights in order to secure successive deflection of portions of the axially flowing motive fluid toward a radial direction. 55

4. In a turbine, a row of exhaust blades adapted to receive motive fluid axially and to discharge it peripherally, each blade comprising an inner approximately radial or plane portion and an outer peripherally-discharging, curved, energy-absorbing portion and being made up of a plurality of sections, and guide members of equal length carried by each of the sections and arranged successively lower from the inlet sides of the blades in order to change the direction of flow of motive fluid from an axial toward a radial direction. 60

5. In a turbine, a row of blades adapted to receive motive fluid axially and to discharge it peripherally and a plurality of deflector members of substantially equal lengths arranged there between and adapted to successively deflect portions of the 70 axially flowing motive fluid toward a radial direction. 75

6. In a turbine, a row of blades adapted to receive steam axially and to discharge it peripherally, means for successively dividing the in-flowing annulus of steam into a plurality of annuli and for changing the direction of flow of the latter from an axial toward a radial direction, and supporting means for the last named means secured to 80 the blades for bracing the latter. 85

In testimony whereof, I have hereunto subscribed my name this 17th day of April, 1922.

ROBERT C. ALLEN.
